UNITED STATES PATENT OFFICE.

LEON COUNTY, OF WINDSOR, MISSOURI.

SAFETY DEVICE FOR ELEVATORS.

1,341,112.

Specification of Letters Patent. Patented May 25, 1920.

Application filed September 23, 1919. Serial No. 325,720.

To all whom it may concern:

Be it known that I, LEON COUNTY, a citizen of the United States, and a resident of Windsor, in the county of Henry and State 5 of Missouri, have invented certain new and useful Improvements in Safety Devices for Elevators, of which the following is a specification.

My invention relates to improvements in 10 safety devices for elevators.

An important object of my invention is to provide an improved safety device for elevators in which the elevator will be securely and positively locked to the guide 15 rails when the supporting cable of the elevator breaks or does not serve to support the elevator whenever it is in danger of falling, irrespective of its position in the elevator shaft.

Another important object is to provide an 20 improved safety device of simple and durable construction and in which the locking means will be so constructed, arranged and actuated as to be positive and reliable in 25 operation.

Other objects and advantages reside in the certain novel features of the construction, arrangement and combination of parts 30 and will become apparent as the description proceeds, reference being had to the accompanying drawings forming part of this specification and in which:

Figure 1 is a front elevational view of an elevator equipped with my improved safety 35 device,

Fig. 2 is an elevational view of one side of the elevator looking from the inside, parts being broken away for the sake of illustration,

Fig. 3 is an elevational view of the same 40 side but taken from the outside of the elevator, parts being broken away for the sake of illustration.

Referring to the drawings my invention 45 includes an elevator of any conventional type shown for the sake of illustration as including a platform frame A having a platform or floor B secured to the top thereof and provided with lift rods C secured there- 50 to and having their upper ends terminat- ing in eyes C' which are adapted to be engaged with supporting connections D' of the supporting cable D. Guide rails E of conventional construction coöperate with

elevator guides F which are mounted on the 55 elevator in a manner to be hereinafter more fully described.

A pair of standards 10, preferably of metallic material are arranged on each side of the elevator and are secured adjacent 60 their lower ends to the rectangular frame A of the elevator platform. The standards of each pair are spaced from each other and each of the standards of one pair are connected at their upper ends by cross bars 11 to 65 the corresponding standards of the other pair. These cross bars 11 are secured to the standards by having portions 11' at each of their ends bent at right angles and bolted to the standards as shown in the 70 drawings. It is obvious that the standards being spaced the cross bars are also spaced.

A vertically reciprocating slide 12 is ar- ranged between the standards 10 and is pre- 75 vented from outward displacement by flat- tened bars 13 bolted to the outside of said standards and extending across the space be- 80 tween the standards. Adjacent the upper and lower ends of the standards and extend- 85 ing transversely to the outside thereof and secured thereto are plates 14. These plates and the standards are provided with alined 85 bearings in which are journaled operating rock shafts 15. As shown these bearings and rock shafts are preferably four in num- 90 ber. The rock shafts extend entirely across the elevator and through the standards and have fixed to each of their outer ends lock- 95 ing dogs 16 adapted to be engaged with the guide rails of the elevator in a manner to be hereinafter more fully described.

As shown in the drawings these rock 100 shafts are arranged in pairs, one pair ar- ranged at the upper end of the elevator struc- 105 ture and the other pair at the lower end thereof and the shafts of each pair are ar- ranged on opposite sides of the elevator 110 guide rails. In this manner the locking dogs carried by the upper and lower shafts on one side of the guide rail bite into or engage the face thereof at points directly 115 opposite to the points at which the locking dogs of the upper and lower shafts on the other side engage the opposite face thereof. The points at which the locking dogs engage 120 the guide rails are immediately adjacent the elevator guides "F" which are secured to the standard as shown.

Adjacent the inner side of the standards 10 the rock shafts are provided with radial arms 17 which are suitably recessed and bored to be pivotally connected to links 18 5 which in turn have their outer ends pivotally connected to offset portions 19' of connecting rods 19. These connecting rods are secured in any suitable manner by bolts or nuts or otherwise to the slides 12. 10 Each of the slides 12 is provided with a lug 12' which extends inwardly therefrom at right angles thereto between the spaced cross bars 11. A three-arm rock lever 20 is mounted for oscillating motion on a trans- 15 verse shaft 21 extending between the cross bars 11. As shown in Fig. 1 there are two of these three-arm rock levers, one arranged adjacent each of the slides 12. Each of these levers has an inner and downwardly 20 curved arm adapted to be engaged with the end of the retractile spring 22, an outer and upwardly curved arm adapted to be engaged with the lug 12' of the slide and an upwardly extending arm adapted to be engaged 25 by the auxiliary connections 23 of the supporting cable D.

In operation the elevator is supported by the supporting cable D, the lift thereof being transmitted through the supporting connections and the lift rods to the platform. 30 While the supporting cable is exerting its normal or lifting force the auxiliary connections 23 have rotated the rock levers 20 against the action of the retractile spring 22 35 to lift the slides 12 and attached connecting rods vertically and thereby through the medium of links 18, and radial arms 17 cause the locked shafts 15 to rotate to swing the locking dogs out of engagement with the 40 elevator guard rails E. When the elevator is falling or in danger of falling by reason of the supporting cable D breaking or not serving to support the elevator, or for other reasons the auxiliary connections slacken 45 and no longer serve to maintain the upward extending arms of the rock lever in raised position. The retractile spring 22 then acts to reversely rotate the rock levers and move the slides, connecting rods, etc., vertically 50 downward to rotate the shaft 15 in such direction as to force the locking dogs into positive engagement with the guide rails E. Any tendency for the elevator to fall will 55 only serve to more tightly bind the locking dogs in locking engagement increasing in proportion to the tendency to fall. In this manner the elevator is securely locked in position and will only be released upon the supporting cable resuming its supporting 60 functions. It is to be noted that the stresses incident to the locking action are evenly distributed throughout the elevator structure, due to the arrangement of the locking dogs and their simultaneous action effected 65 as previously set forth. Moreover the lock-

ing action is complete, positive and effective irrespective of the load carried, or the distribution of this load on the platform.

I claim:

1. A safety device for elevators comprising the combination with an elevator platform, a lifting cable therefor, elevator guides associated with said platform and guide rails coöperating therewith, of spaced standards secured to each side of the elevator platform, spaced cross bars connecting said standards, a vertically movable slide arranged between each pair of standards, rock shafts journaled in each of said standards adjacent their upper and lower ends, locking dogs fixed to the outer ends of said rock shafts and adapted to be engaged with the elevator guide rails, radial arms secured to said rock shafts, a connecting rod fixed to each of said slides, links connecting said radial arms and said connecting rods, a three-arm rock lever arranged between said spaced cross bars having one arm thereof engaged with said slides, a retractile spring engaging another arm of said lever and auxiliary connections from said supporting cable engaged with the other arm of said lever as and for the purpose set forth. 70 75 80 85 90

2. A safety device for elevators comprising the combination with an elevator platform, a lifting cable therefor, elevator guides associated with said platform and guide rails coöperating therewith, of a pair of standards secured to each side of the elevator platform, a vertically movable slide arranged between each pair of standards, rock shafts journaled in each of said standards adjacent their upper and lower ends, locking dogs fixed to the outer ends of said rock shafts and adapted to be engaged with the elevator guide rails, radial arms secured to said rock shafts, a connecting rod fixed to each of said slides, links connecting said radial arms and said connecting rods, a three-arm rock lever arranged between said spaced cross bars having one arm thereof engaged with said slides, a retractile spring engaging another arm of said lever and auxiliary connections from said supporting cable engaged with the other arm of said lever as and for the purpose set forth. 95 100 105 110 115

3. A safety device for elevators comprising the combination with an elevator platform, a lifting cable therefor, elevator guides associated with said platform and guide rails coöperating therewith, of rock shafts, locking dogs fixed to said rock shafts and adapted to be engaged with said guide rails, means connecting said rock shafts and adapted to simultaneously move same to locking or release position, a three-arm rock lever having one arm engaged with said means, a retractile spring engaging another 120 125 130

arm of said lever and auxiliary connections from said supporting cable engaged with the other arm of said lever all as and for the purpose set forth.

5 4. A safety device for elevators comprising the combination with an elevator platform, a lifting cable therefor, elevator guides associated with said platform, and guide rails coöperating therewith, of a pair 10 of rock shafts arranged at the upper and lower ends of said elevator structure, the shafts of each pair being disposed on opposite sides of the elevator guide rails, locking dogs fixed to said shafts and adapted 15 to be engaged with said guide rails, a vertical slide connected with said rock shafts, a vertically swinging lever connected with said slide, the axis of said lever being disposed at right angles to the axes of said rock 20 shafts, a retractile spring engageable with said lever and an auxiliary connection from said lifting cable engageable with said lever, all as and for the purposes set forth.

5. A safety device for elevators comprising

ing the combination with an elevator plat- 25 form, a lifting cable therefor, elevator guides associated with said platform and guide rails coöperating therewith, of spaced standards secured to each side of said elevator platform, spaced cross bars connect- 30 ing said standards, a pair of rock shafts ar- ranged at the upper and lower ends of said elevator structure, the shafts of each pair being journaled in said standards on oppo- 35 site sides of the elevator guide rails, lock- ing dogs fixed to said rock shafts and adapted to be engaged with said guide rails, a vertical slide arranged between each pair of spaced standards and connected with said rock shaft, a pair of vertically swing- 40 ing levers journaled in said cross bars, a retractile spring arranged between said cross bars and having its ends engaged each 45 with one of said levers, and auxiliary connections from said lifting cable engageable with said levers, all as and for the pur- poses set forth.

LEON COURTY.
